DESIGN FOR A DIAL FOR BAROMETERS OR THE LIKE

Frank J. Scott, Minneapolis, Minn.

Application January 16, 1942, Serial No. 105,235

Term of patent 14 years

To all whom it may concern:

Be it known that I, Frank J. Scott, a citizen of the United States and residing in the city of Minneapolis, county of Hennepin, and State of Minnesota, have invented a new, original, and ornamental Design for a Dial for Barometers or the like, of which the following is a specification, reference being had to the accompanying drawing, forming a part thereof, where-in—

The figure is a front view of a barometer dial showing my new design. Portions of the drawing have been lined to indicate contrasting colors.

I claim:

The ornamental design for a dial for barometers or the like, substantially as shown and described.

FRANK J. SCOTT.
